COMBINED BAR AND COFFEE TABLE

Douglas H. McCraw, Hawthorne, Calif., assignor to Abco Metal Products, Inc., Hawthorne, Calif., a corporation of California

Application February 21, 1955, Serial No. 34,598

Term of patent 14 years

(Cl. D33—19)

FIG. 3

FIG. 5

FIG. 4

Fig. 1 is a front perspective view of my combined bar and coffee table, in bar position;

Fig. 2 is a rear perspective view of the same;

Fig. 3 is a top perspective view of the same in coffee table position;

Fig. 4 is an end elevational view of the same in bar position;

Fig. 5 is an end elevational view of the same in coffee table position.

I claim:

The ornamental design for a combined bar and coffee table, substantially as shown.
